UNITED STATES PATENT OFFICE.

JOHN FREEMAN MACKAY, OF BORDENTOWN, NEW JERSEY.

BROODER.

1,163,936.

Specification of Letters Patent. Patented Dec. 14, 1915.

Original application filed June 17, 1913, Serial No. 774,149. Divided and this application filed June 18, 1914. Serial No. 845,870.

To all whom it may concern:

Be it known that I, JOHN F. MACKAY, a citizen of the United States, residing at Bordentown, in the county of Burlington and State of New Jersey, have invented certain new and useful Improvements in Brooders, of which the following is a specification, reference being had therein to the accompanying drawing.

10 This invention relates to brooders for raising incubator hatched chicks, and the principal object of the invention is to produce a simple and efficient colony brooder suitable for use either indoors or in the 15 open and which will accommodate and safely care for a large number of chicks.

In the accompanying drawing has been illustrated a simple and preferred form of the invention, it being, however, understood 20 that no limitation is necessarily made to the precise structural details therein exhibited, but that changes, alterations and modifications within the scope of the claims may be resorted to when desired.

25 In the accompanying drawing—Figure 1 is a side elevation, partly in section, of a device constructed in accordance with the invention. Fig. 2 is a top plan view of the same.

30 Corresponding parts of the several figures are denoted by like characters of reference.

The heater of the improved brooder consists of a stove or furnace A, of which 5 designates the fire box, 6 the grate, and 7 the ash pit,—for which a draft door 8 is provided, said door being hinged at its upper edge, as shown, so that it will naturally 35 gravitate to a closed position. The stove body, which has been shown as tapering upwardly, is provided at its upper end with a hopper B, the discharge opening of which, 9, is adapted to constitute a seat for a valve or damper 10. The hopper B, the 40 upper portion of which flares beyond the stove body, is provided with a top plate 11 having an opening covered by a lid 12 which is directly above the discharge opening 9 of the hopper. The lid 12 is apertured over 45 the valve or damper 10. The top plate has an opening 14 which is located at one side thereof substantially in vertical alinement with the draft door 8; a valve or damper 15 whereby said opening may be obstructed 50 55 is hinged adjacent to the outer edge of the opening, said damper being provided with

an outwardly extending arm 16. A flue 17 for carrying off the products of combustion is mounted on the top plate 11.

Fulcrumed on a support 18 which rises 60 from the top plate 11 is a lever 19, one arm of which is connected with the valve stem 13 and with one end of a flexible element 20, which latter is connected at its lower end with the damper 8 and intermediate its ends 65 with the arm 16; the other arm of the lever 19 carries a counterweight 21 for approximately balancing the valves 10, 15 and 8. The parts are so arranged that when the door or valve 8 is wide open, the valve 15 70 will be seated, and the valve 10 will, likewise, be wide open to permit products of combustion to pass from the fire box to the exit flue 17. As the valves 8 and 10 move in the direction of their respective seats the 75 check valve or damper 15 will gradually be unseated.

A thermostat 21' is supported on a bracket 22 extending from the stove body, said thermostat including a rod 23 which is 80 guided through an aperture 24 in a portion of the top plate 11 which overhangs the stove body. The rod 23 is connected with the arm of the lever 19 that carries the counterweight 21 by means of an intermediate lever 26 fulcrumed on the upright 18 and a connecting member 28, said lever and connecting member being introduced for the purpose of increasing the movement of the lever 19 relatively to that of the rod 23, 90 thereby rendering the operation of the device more effective. 85

The top plate 11 supports a downwardly flaring hood D which for convenience is preferably composed of hingedly connected 95 members 29, 30, one of which may, furthermore, be provided with a door 31 through which access may conveniently be had to the interior for the purpose of removing ashes from the ash pit 7, and the like. A curtain 100 32 of flexible material depends from the lower edge of the hood D and terminates a short distance above the ground so as to afford ample protection while not hindering the ingress and egress of the chicks. 105

By making the hood of separate parts, as shown, and hinging them together, as at 33, I am enabled to make use of a coal or solid fuel burner of the specific form shown, or of other suitable construction, and apply 110 the hood thereto easily and quickly. It will be seen that the hood is in the form of a

2
truncated cone, and this shape is especially advantageous since it permits the hood to be closely fitted to the top 11 of the heater without necessitating especial and nice machine or hand work in the construction of the parts to insure that they shall fit together with sufficient accuracy to secure practically closed joints. The top of the heater, as here understood, is that part, or 10 those parts, carried by the heater to which the upper edge of the hood is applied, and which serves to constitute the top of the brooder chamber inclosed by the hood.

The operation and advantages of this invention will be readily understood from the foregoing description taken in connection with the drawings. Coal may be conveniently fed to the stove by manipulating the lever 19 so as to raise the valve 10 to a non-obstructing position and then sliding the lid 12 upwardly upon the valve stem; the fuel may then be introduced and will be guided over the downwardly inclined wall of the hopper through the aperture 9 and 20 into the fire box. The valves or dampers will be automatically operated to regulate the draft so as to maintain the temperature evenly at a predetermined degree. The general construction is simple, inexpensive, and 25 thoroughly efficient for the purpose for which it is provided.

A thermometer 35 is provided to enable the temperature within the hood to be ascertained, and the hood may have a hand 35 hole, 36, through which the thermometer is accessible.

It will be seen that the top plate covering the hopper extends laterally beyond the perimeter thereof all around the heater. This 40 is a decidedly advantageous arrangement in a heater for a brooder, as it permits a hood of simple truncated cone form like that illustrated, to be easily applied to and supported by the said plate, no particular fitting and shaping of the parts with reference to each other being necessary to secure practically air-tight joints when they are united. It will also be observed that the means by 45 which the draft-controlling dampers, 8 and 15, and the closure 10, are controlled—the levers 19, 26, etc.—are supported by the said top plate, thus making a self-contained apparatus, or one supported by a single base. The check draft opening 14 is in the top 50 plate and hence exposed, so that when the damper 15 is open the air taken in to check the draft is drawn from the open, and not from within the hood D, so that the temperature within the latter is not lowered by 55 the inflow of outside air when the check damper is opened. Furthermore, by making the heater with an opening in its top 60 through which fuel may be fed to the fire

chamber, and applying the hood so that it surrounds the heater but does not cover the top, I am enabled to practically use a coal or other solid fuel burner as the heater for a brooder and to replenish the fire with fuel from time to time as occasion requires, without having to open the brooder chamber, 70 with the incident disadvantage of the loss of heat and danger from the confined air being contaminated by the escaping gases of combustion.

I do not in this case claim the specific 75 form of heater herein illustrated and described, as that is made the subject matter of Letters Patent granted to me July 14, 1914, No. 1,103,837.

What I claim is:—

1. In a brooder, the combination with a heater, of a hood supported thereby and spaced from the walls thereof, the said hood being vertically divided to produce separate members which are hingedly connected 85 together to permit the hood to be conveniently applied to and detached from the heater.

2. In a brooder, the combination with a heater provided with a circular top, a downwardly-flaring hood supported by the top and spaced from the heater and also open so as to expose the top of the heater and permit access to be had to the interior of said heater without disturbing the hood, the hood being of truncated conical form, and vertically divided to produce separate members which are adapted to be hinged together 95 about the heater to form a brooder chamber closed above by the said top.

3. In a brooder, the combination with a heater provided with a circular top, a downwardly flaring hood supported by the top and being of truncated conical form, its lower edge being free from the surface on which the heater rests, said downwardly flaring hood being vertically divided to produce separate members which are adapted 105 to be hinged together about the heater to form a brooder chamber closed above by the said top.

4. In a brooder, the combination with a heater having a circular top, a downwardly-flaring hood supported by the top, and being of truncated conical form, and divided vertically to produce separate members which are hinged together so as to surround the heater and form a chamber closed above by the top of the heater.

In testimony whereof I affix my signature 120 in the presence of two witnesses.

JOHN FREEMAN MacKAY.
